GAME BOARD OR SIMILAR ARTICLE

Walter C. Milewski, 3912 Market St., Camp Hill, Pa.

Filed Dec. 7, 1962, Ser. No. 72,768

Term of patent 14 years

(Cl. D34—5)

Fig. 1

Fig. 2

FIGURE 1 is a plan view of a game board or similar article, showing my new design; and

FIGURE 2 is an end elevational view thereof.

The characteristic feature of my design resides in the combination on the game board of the direction arrows arranged on the pathways and the particular ornamentation on the central portion of the board, all as shown.

I claim:

The ornamental design for a game board or similar article, substantially as shown and described.
